Patented Sept. 26, 1922.

UNITED STATES PATENT OFFICE.

THOMAS T. BATHURST, OF KANSAS CITY, MISSOURI.

SPARK PLUG.

Application filed November 12, 1921. Serial No. 514,433.

To all whom it may concern:

Be it known that I, THOMAS T. BATHURST, a citizen of the United States, residing at Kansas City, in the county of Jackson and State of Missouri, have invented certain new and useful Improvements in Spark Plugs; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to spark plugs and the primary object thereof is to provide a rugged, durable, inexpensive and efficient plug, the construction being such that provision is made for renewals in a most convenient manner.

The invention contemplates the provision of means whereby the porcelain which carries the positive electrode may be confined within a casing consisting of a plug or skirt member to be screwed into the engine cylinder wall and a separate cap member. The skirt member may be installed as a permanent part of the engine cylinder with the cap member removable therefrom so that the porcelain may be removed for inspection, repairs or renewals.

20 The cap member is adjustable with respect to the skirt member in which the porcelain is seated so that the porcelain may unseat during the compression stroke of the engine to permit the fuel charge to be forced past the electrodes to free them as well as the lower portion of the porcelain of carbon deposits or other extraneous matter.

25 Upon the suction stroke of the piston the porcelain will seat so as to valve off the orifice surrounded by the wall of the skirt member and prevent the admission of atmosphere through the spark plug into the engine. Therefore, it will be apparent that the porcelain may function as a check valve during the operation of cleaning the electrodes or during the time that the engine is being tested for compression or to determine 30 whether or not the spark plug electrodes are properly functioning.

The portion of the porcelain which is seated within the skirt member or portion is provided with a covered shoulder curved on 35 a different arc than the curvature of the seat so that there will be a line contact between

the porcelain and its seat. This is an advantage over a flat contact because liability of leakage due to interposition of carbon or gritty matter will be eliminated.

40 Means is also provided for eliminating liability of cracked porcelains due to variations in the coefficients of expansion between the spark plug shell or casing and the porcelain and to this end I arrange about the porcelain a shell having certain yielding portions which contact with the skirt member and the cap member so that the porcelain may expand without contacting directly with either the skirt member or the cap member. 45 The tendency to expand, however, is reduced by reason of the fact that a cooling space is provided about the porcelain so as to maintain the temperature of the porcelain relatively low.

50 Another advantage in the construction of the device is that the engine can be primed through the spark plug by introducing fuel liquid into the cylinder therethrough and I have also provided means whereby liability 55 of the space between the positive and negative electrodes becoming great enough to cause mis-fire will be prevented.

The specific construction of the preferred embodiment of my invention as well as the 60 novel details of construction will be apparent by reference to the following description in connection with the accompanying drawings, in which—

Fig. 1 is a side elevational view of a spark 65 plug constructed in accordance with my invention.

Fig. 2 is an enlarged, vertical, longitudinal, sectional view through the spark plug casing or shell.

Fig. 3 is an enlarged view partly in elevation and partly in section through the removed porcelain.

Fig. 4 is a vertical, longitudinal, sectional view through the spark plug showing the 100 porcelain unseated to permit the exhaustion of the contents of the combustion cylinder therethrough or to permit priming into the cylinder.

Fig. 5 is a similar view of the porcelain 105 seated so as to valve the skirt member of the casing or shelf, and

Fig. 6 is a detail perspective view of the parts disassociated, showing the introduction of the porcelain as a renewal or during 110 the assembly.

The spark plug shell or casing is shown as

consisting of two members 1 and 2. I designate the member 1 the skirt member because it consists of a cylindrical body having a central longitudinal orifice 3 and divided into a threaded skirt portion 4 and an upper threaded collar 5, the lower end of the skirt carrying the negative electrodes 6 and 7 connected to the lower end of the skirt portion 4 at diametrically opposite points 10 and having parallel ends 8 and 9, the purpose of which will be described hereinafter.

The skirt member is separated from the collar 5 by a polygonal collar 10, by means of which a wrench may be used to introduce 15 the threaded skirt portion into the threaded portion 11 of the engine cylinder 12 (see Fig. 6).

The skirt member is provided at its upper end with a porcelain-receiving seat 13, upon which the enlargement or collar 14 of the porcelain 15 may rest. The edge 16 of the collar 14 is curved on an arc generated from a shorter radius than that of the seat 13 so that there will be a line contact of the 25 porcelain on the seat, the porcelain being held thereon by the cap member 2, which has a lower internally threaded portion 17 to engage the threaded collar 5, as clearly seen in Fig. 2.

30 The upper end of the collar 14 is engaged by a seat or flange 18, which rests thereupon and co-operates with the seat 13 to clamp the porcelain rigidly within the shell, the side wall of the cap 2 having a plurality of 35 perforations 19 to permit air to circulate about the collar 14 to permit priming through the orifice 3 and to permit the exhaust from the cylinder to pass to atmosphere when the collar is unseated.

40 By reference to Fig. 3 it will be observed that the collar 14 of the porcelain 15 is a metallic shell of greater length than the porcelain portion 14' and that the shell is spun over the upper and lower portions of the 45 porcelain portion 14' so as to provide resilient or yielding ends 20 and 21 between which and the upper and lower edges of the portion 14' are yielding gaskets 22 and 23.

It will also be observed that the shell is 50 slightly larger in diameter than the part 14' so if the portion 14' expands, it may expand within the space between the wall of the collar 14 and the porcelain portion 14', thereby preventing liability of crushing effect of the 55 rigid shell against the portion during its expansion. If the porcelain grows or expands longitudinally, its expansion can be provided for by the gaskets 22 and 23 as well as by the yielding flanges 20 and 21. Therefore it 60 will be apparent that there can be considerable expansion and contraction of the porcelain 15 without liability of the porcelain cracking, which is a serious defect in most plugs now on the market.

65 Attention is also directed to the fact that

the porcelain carries the usual positive electrode 24, extending below the lower end thereof and terminating at its upper end in a binding post 25, in the usual manner.

In actual practice I prefer to have the diameter of the bore 26 of the cap 2 slightly in excess of the shell or collar 14 so that when the upper end of the porcelain 15 projects through the orifice 27, there will be a slight play or wobbling motion of the porcelain as 75 the collar moves off and onto the seat 13. This is an important feature of the invention because the free motion of the porcelain allows it to be self seating; that is, there is no fixed seat for the edge 16 because it is a 80 line contact and it may find a different place to seat each time it is moved onto the seat 13. Therefore, liability of the plug leaking after extended use will be reduced to a minimum.

Since the spark plug shell or casing 85 consists of but two members adjustably connected together with one of the members so constructed that it may be screwed into the engine cylinder as a permanent part thereof, it will be apparent that an extremely efficient 90 means is provided for renewals. For example, the porcelain can be constructed as shown in Fig. 3 as a unitary structure so that in the event that it becomes necessary to take out the porcelain for inspection, repairs or, more important, for renewals, it 95 will be only necessary to unscrew the cap member 2, remove the porcelain and, if a renewal is required, introduce a new porcelain, screw back the cap, and the plug is 100 complete.

The efficiency in making the renewal is due to a large extent to the fact that the line contact is provided so that the porcelains are interchangeable in any of the skirt 105 portions and do not have to be set especially for any particular plug casing and because there is a line contact, the fact that a porcelain has been in the plug for some time will not prevent the renewal from perfectly fitting the first time it is introduced into the old shell.

By providing the parallel, oppositely directed fingers 8 and 9, which constitute the negative electrode, it will be apparent that 115 though the fingers 8 and 9 expand or warp, they will never be a distance away from the end 28 of the positive electrode 24 sufficient to prevent the spark to bridge the gap between them because the fingers will not warp 120 more than their widths but if for any reason they should get bent out of shape, it will still be possible to make them properly function because there will always be a portion of a negative electrode sufficiently close to the end 125 28 to permit the proper functioning of the plug.

When the parts are assembled and it is desired to clean the plug, it will be only necessary to slightly back screw the cap 2. There- 130

fore, the incoming raw charge of fuel introduced into the combustion cylinder may be forced over the electrodes and lower portion of the porcelain and out through the ports 5 or holes 19. On the suction stroke of the piston, however, the porcelain will re-seat itself, as shown in Fig. 5, so that atmosphere will not be drawn through the plug, the cleaning charge in each instance being the 10 fuel itself and since it is usually gasoline, it will be apparent that the porcelain and electrodes can be readily cleaned.

If it is desired to prime the engine, the cap will be back screwed and the porcelain 15 lifted to the position shown in Fig. 4, whereupon, a charge may be introduced through the ports 19, through the bore 3 and into the combustion chamber of the cylinder.

20 Whenever it is desired to renew or inspect the porcelain, this can be accomplished by removing the parts, as shown in Fig. 6, it being readily apparent that the renewal feature is a very important 25 part of the invention.

Aside from the other advantages, the porcelain is so constructed that liability of cracking due to expansion will be practically eliminated.

30 Attention is also directed to the fact that since the bore 26 is slightly larger in diameter than the collar 14 so as to provide a space, air is permitted to circulate through the ports 19 and between the collar and the 35 surrounding wall of the cap 2 so as to maintain the temperature of the porcelain at its thickest portion relatively low and since the collar 14 is spun over the portion 14' with the lower flange 21 resiliently disposed 40 with respect to the end portion 14', it will be apparent that when the porcelain functions as a check valve to seat and unseat when the parts are in the position shown in Figs. 4 and 5, the blow or impact of the 45 porcelain against the seat 13 will not result in breaking or chipping of the porcelain which might be true if the porcelain came in direct contact with its seat. Therefore, the reciprocatory action of the porcelain will not result in any ill effect on the 50 porcelain.

It should be remembered that when the porcelain is moved off its seat, the compression in the combustion chamber is destroyed. The spark will still bridge the 55 gap between the end 28 of the electrode 24 and the electrodes 7 and 8 but no explosion can take place because the fuel charge will not be under compression. Therefore, the 60 lower intake charge will be forced over the electrodes 7 and 8 and around the porcelain to act as a cleansing fluid to remove accumulated carbon, the raw fuel charge being more efficacious than the exploded 65 charge; hence, I can provide means for dis-

tributing or contacting the raw fuel charge over the parts to be cleaned without any special attention other than to back screw the cap 2 to permit the porcelain to move off its seat and destroy the compression, 70 which is essential to combustion in an engine of the type to which the plug is to be attached.

Therefore, it will be seen that the device is inexpensive, rugged, efficient and that 75 it eliminates practically all of the causes of trouble heretofore encountered in various types of spark plugs.

What I claim and desire to secure by Letters Patent is:

80 1. A spark plug comprising a skirt member and a cap member, the skirt member having a seat, a porcelain having a shoulder to rest upon the seat, the arc of the shoulder being less than the arc of the seat whereby 85 a line of contact is provided between the porcelain and the seat and means for adjustably securing the cap to the skirt member, the cap member being adapted to normally hold the porcelain rigid with respect 90 to the skirt member and adapted to be adjusted on the skirt member to allow the porcelain to reciprocate from and toward its seat.

95 2. A porcelain for spark plugs comprising a porcelain body having a central electrode extending therethrough, one end of which constitutes a binding post and the other a contact point, the porcelain having an intermediate rigid collar providing upper and lower shoulders, a resilient shell surrounding the collar having flanges projecting over the upper and lower shoulders and cushions between the flanges and the shoulders to provide resilient bearing surfaces.

100 3. A spark plug comprising a skirt member and a cap member, the skirt member having a tapered seat at its upper end, the cap member having a central opening at 110 its upper end surrounded by a flange constituting a seat, a porcelain having a collar interposed between the two seats and adapted when the cap is in the one position to reciprocate between the two seats, said collar forming a shoulder, the arc of the shoulder and the arc of the seat being such that a narrow line of contact is established, yielding contacts on the porcelain for engagement with the respective seats, the 115 flanged opening of said cap loosely engaging said porcelain to cause the same to properly seat itself on said tapered seat.

120 4. A spark plug comprising a skirt member and a cap member, the skirt member having a tapered seat at its upper end, the cap member having a central opening at 125 its upper end surrounded by a flange constituting a seat, a porcelain having a collar interposed between the two seats, and a me- 130

1
talic casing about the collar but spaced from the periphery thereof, the ends of the casing being turned over at the ends of the collar, resilient seats between the ends of the collar and the ends of the casing, the arc of the ends of the casing of said tapered seat being such that a narrow line of contact is established, the flanged opening of said cap loosely engaging said porcelain to cause the same to properly adjust and seat itself on said tapered seat. 10

In testimony whereof I affix my signature.

THOMAS T. BATHURST.
